UNITED STATES PATENT OFFICE.

JACOB A. JOHNSON, OF OTTAWA, KANSAS.

FENCE-POST.

1,001,274.

Specification of Letters Patent. Patented Aug. 22, 1911.

Application filed January 2, 1909, Serial No. 470,322. Renewed February 1, 1911. Serial No. 606,009.

To all whom it may concern:

Be it known that I, JACOB A. JOHNSON, a citizen of the United States, residing at Ottawa, in the county of Franklin, State of Kansas, have invented certain new and useful Improvements in Fence-Posts; and I do hereby declare the following to be a full, clear, and exact description of the invention, such as will enable others skilled in the art 10 to which it appertains to make and use the same.

The present invention relates to improvements in metallic fence posts, and it has for its primary object the provision of an 15 extremely simple, light and durable post constructed in such a manner as to permit the fence wires to be readily and securely fastened thereto at any desired distance from each other. To this end, the post has 20 its front face provided with cross grooves arranged to receive the wires, the latter being held in place therein by means of staples which are passed through vertical slots formed in the post and opening through 25 both faces thereof, the slots intersecting the grooves above mentioned, the ends of the staples being bent laterally outward in opposite directions and clenched around pairs of shoulders formed on the rear face of the 30 post, thus securely holding the wires against displacement.

The preferred embodiment of the invention is illustrated in the accompanying drawings in which corresponding parts are 35 designated by the same reference numerals throughout the several views.

Of the said drawings, Figure 1 is a front elevation of the post, showing the wires attached thereto. Fig. 2 is a rear elevation of 40 Fig. 1. Fig. 3 is a section taken transversely through Fig. 1 on the line 3—3.

Referring more particularly to the drawings, the post 5, which is formed of cast iron, is shown as provided with a series of longitudinal slots 6 arranged in vertical alignment, the slots opening through both faces 45 of the post and being spaced any desired distance from each other. Each slot intersects a vertical series of transversely-disposed parallel grooves 7 formed in the outer face of the post, the height of the series being equal to the length of the slot. These series of grooves are designed to interchangeably receive the fence wires 8, there being, preferably, one wire to each series, although this

is not positively essential, since the number of wires employed may be varied at will.

Each wire is held in its groove by means of a staple 9, which is inserted in the corresponding slot, the free ends of the legs of the staple projecting beyond the rear face of the post, in which face is formed a pair of parallel vertical grooves 10, said grooves being arranged upon opposite sides of the slot and extending from end to end of the 60 post, as shown in Fig. 2. This particular disposition of the grooves results in the formation of a vertical rib 11 co-extensive in length therewith, the several slots opening through the rib, as is likewise shown in 65 said figure, thus virtually bifurcating the rib at intervals, and forming a series of pairs of parallel shoulders 12, which are located exactly at the inner side edges of the slots and have a length equal to that of said 70 edges. The walls of the slots slope toward each other, so that the distance between the inner side edges thereof is less than that between the outer side edges.

In attaching the fence wires, each is fitted 75 in one of the grooves 7, after which a staple is engaged therewith and passed rearwardly through the slot by which the groove is intersected. The staple is then held in place by a hammer or similar implement held in 80 one hand of the operator who, by means of a hatchet which he holds in his other hand, turns the projecting ends of the staple legs in opposite directions, and clenches them over the shoulders 12, the walls of which, as 85 shown in Fig. 3, are oppositely inclined. The remaining wires are then fastened to the post in the same manner.

As originally stated, the number of wires employed is preferably equal to the number 90 of slots, there being in such instance, one wire for each series of transverse grooves. It will be apparent, however, as likewise stated, that such number may be increased or diminished; and it will be understood that 95 the formation of the series of grooves just mentioned permits the wires to be arranged at equal or different distances apart from each other, since the wires may be fitted in any of the grooves of the several series.

The shoulders 12 formed by the slots opening through the rib 11 present surfaces against which the terminals of the staple legs may be readily clenched, the opposite 100 inclination of such surfaces preventing acci- 110

dental displacement and disengagement of the staples.

What is claimed is:—

A fence post formed with a portion of its front face flat and with a series of alining vertical slots, the walls of each of which slots converge from the front to the rear of the post, and having a plurality of series of parallel transverse wire receiving grooves formed in the flat portion of its front face whereby wires disposed therein are held against movement longitudinally of the post, each series of grooves being intersected as an entirety by one of said slots, a vertical rib formed on its rear face through which said slots open, the walls of said ribs being continued laterally in opposite directions to

form vertically disposed grooves on each side of said ribs, in combination with a one piece staple adapted to receive a wire and pass through the slot and having its ends bent laterally in opposite directions to follow respectively the transverse contours of the sides of said rib and the adjacent grooves; said staple serving to draw the wire received thereby inwardly and maintain same positively seated in a wire receiving groove.

In testimony whereof, I affix my signature, in presence of two witnesses.

JACOB A. JOHNSON.
